(57) **CLAIM**

I claim the ornamental design for a toy crossbow, as shown.

DESCRIPTION

FIG. 1 is a rear perspective view of a toy crossbow showing my new design;

FIG. 2 is a front perspective view thereof;

FIG. 3 is a left side view thereof;

FIG. 4 is a right side view thereof;

FIG. 5 is a top view thereof;

FIG. 6 is a bottom view thereof;

FIG. 7 is a front view thereof; and,

FIG. 8 is a rear view thereof.

The broken lines and areas within them in FIGS. 4, 5, and 6 depict portions of the toy crossbow that form no part of the claimed design.

1 Claim, 8 Drawing Sheets
